RICHARD KONRAD HERTEL, OF LOS ANGELES, CALIFORNIA.

THERMOSTATIC CONTROL.

Application filed November 26, 1923. Serial No. 677,193.

To all whom it may concern:

Be it known that I, RICHARD KONRAD HERTEL, a citizen of Germany, and resident of Los Angeles, in the county of Los Angeles and State of California, have invented new and useful Improvements in a Thermostatic Control, of which the following is a specification.

This invention relates to a mechanical movement and appertains particularly to a thermostatic control for valves or like apparatus.

It is the primary object of this invention to provide a simple member, wherein a movement is greatly multiplied and wherein the force at the output end is appreciable. Another object of this invention is to provide a cantilever beam whose bending is effected by difference in the forces simultaneously applied longitudinally of the beam. A further object of this invention is to provide a cantilever movement with means to produce a snap action. In addition to the broader objects of this invention there are certain details of structure, whereby a simple, efficient, durable, and positively acting structure is obtained.

These objects together with other objects and corresponding accomplishments are obtained by means of the embodiment of my invention illustrated in the accompanying drawing, in which:

Fig. 1 is a vertical section through a control adapted to be connected to a tank for the storage of hot water; Fig. 2 is a section as seen on the line 2—2 of Fig. 1; Fig. 3 is a section as seen on the line 3—3 of Fig. 1; Fig. 4 is a perspective view of a fragment of the control showing the snap catches; Figs. 5 to 8, inclusive, are diagrammatic views showing the principle of operation of the snap catches; Figs. 9 and 10 are diagrammatic views to illustrate the action of the cantilever; and Fig. 11 is a plan view partly in section of another form embodying my invention.

Referring more particularly to Figs. 1 to 10, inclusive, a water jacket preferably a casting of aluminum or like metal is indicated by 12. This jacket has a passage 13 extending the length thereof, there being

an internally threaded nipple 14 communicating with the top thereof and a similar nipple 15 communicating with the bottom thereof. The structure is such as to permit the circulation of liquid such as water. A shelf 16 extends outwardly from the bottom of the jacket and is provided with an opening to receive a bolt later described. At the top of the body are supports 17 and 18 having flat faces to which the cantilevers are adapted to be connected. Mounted upon the shelf 16 and extending upwardly is a rod 19 preferably formed of steel or metal having a different coefficient of expansion than the metal of which the body is formed. At the top of rod 19 is a threaded stem 20 carrying adjusting nuts for a block 21, whereby the position of the block may be adjusted with respect to the shelf 16.

Secured to the body so as to rest against the support 17 is a metal strap 22. Disposed alongside of strap 22 is a strap 23 which is secured at its upper end to the block 21. These straps form plies of a cantilever beam. The lower ends of the straps are secured together by a rivet 24 so that they can have no relative longitudinal movement at this point. An extension 25 is secured to the straps 22 and 23 by the rivet 24. The lower end of the extension 25 is provided with a laterally extending foot 26 having a toe 27. Secured to the face 18 is a strap 28. Block 21 has secured thereto a strap 29 which lies against strap 28 and forms therewith a two ply cantilever. The lower ends of the straps 28 and 29 are riveted together and have an extension 30 mounted thereon in a manner similar to extension 25. The lower end of extension 30 is provided with a foot 31 having a toe 32. The cantilever beams are disposed so as to lie in planes at right angles to each other, and flexure of the beams will cause the extensions to move to and from each other.

Referring to Figs. 9 and 10, the operation of a cantilever beam movement is illustrated. A and B are straps or plies secured to each other at one end against relative longitudinal movement, the other ends being free. The straps are such that when no pressure or equal pressures are applied to

the straps they will lie in a straight line as shown in Fig. 10. Suppose that a greater pressure is applied to the end of strap A in a longitudinal direction as indicated by the arrow in Fig. 9. This will cause a tendency of the top strap to move toward the fixed end of the beam and a restraint thereof by the bottom strap. The effect is the same as in a beam wherein there is tension on one side and compression on the other. The result is that the beam bends. In the structure shown in Figs. 1 to 8 inclusive, the body 12 expands, whereas the rod 19 remaining cold has substantially no expansion. The result is that there is a difference in pressure. Strap 22 and likewise strap 28 pull upwardly, while straps 23 and 29 have a pressure in the opposite direction. This tends to bend the beams. Upon the jacket becoming colder, there is contraction and a tendency of the beams to bend in the opposite direction. This action causes the extensions to move to and from each other. In normal cold position, the parts are as shown in Figs. 1, 3 and 4. In normal or cold position, the feet and toes are in the position shown in Figs. 4 and 5. The beams as they bend move the feet toward each other simultaneously. Toe 32 will reach a position in front of the path of travel of toe 27 before the latter can pass in front of toe 32. The parts will eventually reach the position shown in Fig. 6. Toe 27, its foot 26 and the beam are thus restrained against movement until toe 32 has reached the position shown in dotted lines in Fig. 6, whereupon toe 27 will snap over to the position shown in Fig. 7. Upon the return movement, toe 32 places itself in front of toe 27, restraining the return of toe 27 until toe 32 has reached the position shown in dotted lines in Fig. 8, whereupon toe 27 and its parts will snap over to the position shown in Fig. 5. This snap action is made use of to control an operating valve which controls the flow of gas or fuel to a burner.

Referring particularly to Fig. 1, a valve case in which there is a valve seat having a port controlling the flow of fuel from one side to the other is indicated by 33. The valve comprises a disk 34 having a stem 35 extending through the casing and abutting extension 25. A compression spring 36 tends to hold valve 34 upon its seat closing the port against the passage of the fuel. Suppose that the nipples 14 and 15 are connected to a hot water tank whose supply of water is heated by a gas burner connected to the valve casing 33. While the water is cold, the parts are in the position shown in Figs. 1, 3, 4, and 5. In this position, the valve disk 34 is off its seat and the burner is being supplied with gas thereby heating the water. As the temperature of the water rises, the jacket 12 also increases in tempera-

ture and expands. This causes the parts to tend to move in the direction indicated by the arrows in Figs. 4 to 6 inclusive. After extension 30 has moved a sufficient distance, extension 25 snaps outwardly to the position shown in Figs. 7 and 8 permitting valve 34 to seat and thereby closing off the supply of gas. Upon the water in the boiler decreasing in temperature, the reverse action occurs and the valve is again opened.

In Fig. 11, a split metallic ring is indicated by 37. To the ends of the ring are secured straps 38 and 39 of a cantilever, the outer ends being secured together by a rivet 40. 41 indicates a ring upon which are mounted rollers 42, the ring 41 and rollers 42 serving as a bearing for the expansible ring 37. Obviously expansion and contraction of ring 41 will cause ring 37 to be expanded and thereby cause flexure of the cantilever at the end, and this may be applied to operate any device desired. For illustration, the ring 41 may be placed about the shell of a cylindrical hot water tank, the heat therefrom causing ring 37 to expand and swing the cantilever. The latter may be connected to a fuel valve operating mechanism.

What I claim is:

1. A cantilever movement comprising a plurality of plies forming a beam, means securing said plies together against longitudinal movement at one end, a thermally expansible member secured to one of said plies so as to apply stresses longitudinally thereof, the other of said plies being held against longitudinal movement.

2. A thermostatic control comprising a pair of cantilever movements as specified in claim 1, the beams being formed of resilient material disposed with their planes at right angles, extensions on said beams disposed to be moved into the path of travel of each other whereby movement of one beam will be restrained by the other until the extension on the last mentioned beam has moved out of the path of travel of the extension on the other beam.

3. A thermostatic control comprising a pair of cantilever movements as specified in claim 1, the beams being formed of resilient material and disposed with their planes at right angles and secured to the same thermally expansible member, extensions on said beams disposed to be moved into the path of travel of each other whereby movement of one beam will be restrained by the other until the extension on the last mentioned beam has moved out of the path of travel of the extension on the other beam.

4. A thermostatic control comprising a pair of cantilever movements as specified in claim 1, the beams being formed of resilient material and disposed with their planes at right angles and secured to the same ther-

mally expansible member, extensions on said beams disposed to be moved into the path of travel of each other, whereby movement of one beam will be restrained by the other until the extension on the last mentioned beam is moved out of the path of travel of the other beam, and a controlled device dis-

posed so as to be moved by the restrained beam.

In witness that I claim the foregoing I 10 have hereunto subscribed my name this 15 day of November, 1923.

RICHARD KONRAD HERTEL.
